MATERIALS HANDLING APPARATUS

Dwight Arthur Duncan, Evanston, Ill., assignor to Appleton Electric Company, Chicago, Ill., a corporation of Illinois

Application August 26, 1954, Serial No. 452,278

10 Claims. (Cl. 214—317)

This invention relates in general to materials handling apparatus and in particular to the dumping of materials from containers or hoppers. While not limited to a particular application, the invention finds especially advantageous use in connection with the well-known industrial or "fork lift" truck, permitting convenient dumping of loads from elevated positions.

It is the general aim of the invention to provide apparatus which permits normal handling of material in containers or hoppers—e. g., raising, transporting and lowering by means of industrial lift trucks—yet which makes possible the dumping of materials by tilting of the hopper without first specially anchoring the latter on a support.

A more specific object of the invention is the provision of means for locking a hopper to an invertible support as an incident to rocking of the latter from its normally horizontal position.

It is another object of the invention to provide such apparatus for dumping materials from a hopper which is readily attachable to a conventional fork lift truck.

Further objects of the invention are to provide such apparatus which is simple and inexpensive in construction; which effects dumping of a hopper by tilting of the latter in a forward direction from the fork truck, permitting the latter to be driven directly up to the receiving bin or receptacle; which achieves complete dumping by causing the hopper to be tilted through an angle greater than 90° to a substantially up-side-down position; which utilizes the weight of the hopper and load to cause tilting of the same for dumping, thereby obviating the need for power means; and which requires only a simple operation, such as a pull on a chain, on the part of a workman, to initiate dumping.

Other objects and advantages will become apparent as the following description proceeds, taken in conjunction with the accompanying drawings, in which:

Figure 1 is a perspective view of materials handling apparatus embodying the subject invention and shown in elevated position on a fork lift truck prior to dumping of a load;

Fig. 2 is similar to Fig. 1, showing the dumping operation in process;

Fig. 3 is a perspective view, taken from below, of a preferred form of hopper utilized in the subject materials handling apparatus;

Fig. 4 is a perspective view of the apparatus, with the hopper omitted, and shown in lowered position on a fork lift truck;

Fig. 5 is a perspective view of the apparatus taken from below as it is held in raised position on a fork lift truck;

Fig. 6 is a detail view, partially in section, illustrating self-engaging releasable latch means; and

Figs. 7, 8, and 9 are fragmentary detail views, partially in section, illustrating a supporting platform in its latched, horizontal, initially released, and tilted dumping positions, respectively, and further showing the corresponding positions of novel locking means.

While the invention has been shown and is described in some detail with reference to a particular embodiment thereof, there is no intention that it be limited to such detail. On the contrary, the intention here is to cover all alterations, modifications, and equivalents falling within the spirit and scope of the invention as defined by the appended claims.

Referring now to the drawings, Figs. 1 and 2 depict an exemplary dumping attachment 10 and hopper 11 constructed and cooperating in accordance with the provisions of the present invention. Such materials handling apparatus is shown in connection with a fork lift truck 12, the latter holding the loaded hopper 11 in raised upright position (Fig. 1), or in a forwardly tilted position 15 to discharge the hopper contents into an elevated gravity-feed receiving bin 14 (Fig. 2).

The fork lift truck 12 may take any one of a variety of commercially available and well known forms. That shown in the present case is of the battery-powered, 20 straddle fork type, having an operator's cab 12a mounted on wheels 12b and located behind a vertical standard 12c. A power-operated elevator carriage 12d rides up and down along the standard under the control of the operator and normally carries forwardly extending forks (not shown) which, when lowered, nest between stabilizing feet 12e. As best seen in Fig. 4 the carriage 12d is formed as a generally rectangular, reinforced frame carrying a crossbar 12f insertable through aligned apertures near the upper ends of the vertical members 12g. L-shaped forks (not shown) are normally pivotally received at the upper ends of the bar 12f, the lower ends of their vertical portions abutting a lower carriage plate 12h.

The speed and maneuverability of such fork lift trucks 35 have brought them into wide industrial use for lifting pallets, boxes and hoppers from any level, transporting the same to a desired location, and then lowering such containers into the desired position of rest.

The dumper attachment 10 is intended to cooperate 40 with any one of a number of hoppers 11, permitting the same to be successively and rapidly picked up by the truck 12, transported to a dumping location such as the bin 14, emptied, and then returned to a storage or refilling area. The preferred form of hopper for facilitating this operation is best illustrated in Fig. 3 and comprises 45 a main body 20 forming the materials holding receptacle and set on legs 21 which hold the body in elevated relation from a support surface such as the floor or ground. This permits entry of ordinary forks or the attachment 10, as will be described, between the underside of the hopper 11 and that surface upon which the hopper is resting. Subsequent elevation of the carriage thus raises the hopper for transport. Various structural forms and materials may be used for the body 20 and legs 21 according to the nature of the material to be

50 handled; in the present case the body is of heavy gauge sheet metal which is corrugated for greater rigidity, and the legs 21 are in the form of rectangular steel frames suitably welded along the shorter sides of the body. For 55 cooperating with the attachment 10 in a manner to be explained, the under side of the hopper is provided with a plurality of spaced, parallel transverse ribs 22. Such ribs are ordinarily formed in the bottom of sheet metal hoppers for the purpose of added strength, and it will be understood that they may also be formed on the undersides of wooden hoppers by nailing a suitable number of wooden strips in place.

In accordance with one feature of the invention which permits the hopper to be turned substantially upside down, means beneath the underside of the hopper are provided for defining spaced channels adapted to accommodate horizontal entry of a part of the attachment 70

10. In the present case, horizontal channels 24 extending at right angles to the ribs 22 are created by the welding or other suitable attachment of inwardly extending plates or flanges 25 along the inner sides of the respective legs 21.

Referring next more particularly to Figs. 4-9, the dumper attachment 10 comprises a pair of support members 26 which are adapted to be attached to the fork truck carriage 12d in lieu of the regular forks and which then present forwardly extending horizontal arms. As here shown, the support members 26 have vertical arms 26a which are adapted at their upper ends to be received on the cross bar 12f, their lower ends abutting the carriage plate 12h. Horizontal arms 26b then extend forwardly from the carriage in a manner similar to conventional forks. For entry into the channels 24 beneath the hoppers 11, and for lifting engagement with the under sides of such hoppers, a suitable platform 28, for example, a heavy metal plate, is carried in pivoted relation by the forward ends of the arms to rock between a substantially horizontal position (Fig. 7) and a forwardly tilted position (Fig. 8). As shown best in Fig. 5, a stationary rod 29 is inserted through and fixed in aligned passages formed in the forward ends of the arms 26b, and suitably located lugs 30, welded or otherwise fixed to the bottom surface of the platform 28 are journaled on this rod. It may be observed at this point that the lugs 30 are located slightly rearwardly of the center of the platform 28 so that the latter, and any hopper carried thereby, will tend to tilt forwardly under the influence of its own weight, about the rod 29.

In order to retain the platform 28 in horizontal position, snap acting releasable latch means (Fig. 6) are mounted on the vertical arms 26a and adapted to engage the upper edge of an upturned stop plate 28a at the rear of the platform 28. The stop plate 28a also limits the extent of the platform's entry beneath the hopper 11. While such latch means may take a variety of forms, they are here illustrated as comprising bolts 32 slideable in channels 34 which are welded to the vertical arms 26a. In the bottom of each channel 34, an elongated slot 34a is formed to permit the passage of actuating levers 35 into recesses 32a defined in the bottom of each bolt 32. The levers 35 are fast on a cross shaft 36 which rotationally extends through the arms 26a. Rocking of the shaft 36 and the arms 35 counter-clockwise, therefore, retracts the bolts 32 and permits the platform 28 to tilt forwardly under its own weight. For effecting such retraction of the bolts 32, one end 36a of the rod 36 is turned upwardly and connected with suitable actuating means such as a pull chain 38. The operator thus need only pull on the chain 38 to retract the bolts 32 against the force of a biasing spring 39 connected between the shaft extension 36a and the carriage 12d. This spring tends to rock the shaft 36 in a clockwise direction and to thus hold the latch bolts 32 in their forwardly projecting, locking positions. Additionally, the forward ends of the bolts 32 are provided with inclined camming surfaces 32b which are struck by the lower rear corner of platform 28 as it is returned to its horizontal position so that the bolts are shifted rearwardly and then automatically snapped into locking engagement with the upper edge of the flange 28a.

In keeping with another important feature of the invention, means are provided for automatically engaging the hopper 11 and locking it on the platform 28 as an incident to forward tilting of the latter. Such means are totally out of the way when the platform 28 is latched in its horizontal position, thus permitting the platform to serve in the usual fashion of conventional forks for ordinary lifting and transporting operations. In the presently illustrated form, such locking means comprise at least one locking element 40 (although two are employed in the present case for greater reliability) dis-

posed beneath the platform 28 and pivoted thereto. As illustrated in Fig. 5, the locking elements 40 are fixed on a shaft 41 which is journaled in a series of apertured lugs 42 welded or otherwise fixed to the underside of the platform 28. The locking elements are turned upwardly at their forward ends to create fingers 40a which are insertable through and retractable from suitably located apertures 44 defined in the platform 28. It will be observed that the shaft 41 which mounts the locking elements 40 is located rearwardly of the apertures 44 but forwardly of the rod 29 which pivotally carries the platform 28.

Means are provided for controlling the positions of the locking elements 40 relative to the platform 28 so that the fingers 40a are inserted through the apertures 44 and into locking engagement with the hopper ribs 22 as an incident to tilting of the platform 28. Yet such means also assure that the fingers 40a are retracted from the apertures 44 when the platform is horizontal. This function is here accomplished by stationary cams 45 fixed on the rod 29 and engaged by the rear ends of the locking elements 40 which extend rearwardly from the shaft 41.

In the preferred form, the cams 45 are made as elongated members with their rearward ends smoothly rounded for sliding engagement with the locking elements 40. These cams are rigidly fixed in a generally horizontal position and in rearwardly extending relation to the rod 29. For causing the locking fingers 40a to extend considerably through the apertures 44 just as soon as the platform 28 tilts only a slight amount, the cams are notched on their undersides to thus leave depending, rounded lugs 45a. The upper surfaces of the rear ends of the locking elements 40 are cooperatively formed with rounded projections 40b which nest in the cam notches when the platform is horizontal (Fig. 7), but which ride over the lugs 45a as the platform begins to tilt (Fig. 8).

When the platform is in its horizontal position (Fig. 7), it lays substantially parallel to the longer dimensions of the cams 45, thereby permitting the cooperating rear ends of the locking elements 40 to swing up close to the platform since the latter are forwardly overbalanced with respect to the shaft 41. Thus, the elements 40 lie substantially parallel to the platform with the projections 40b nested in the cams 45, and the fingers 40a are retracted from the apertures 44. However, as the platform begins to tilt forwardly about the rod 29, the cams 45 remain stationary and the locking elements 40 are shifted rearwardly with respect to the cams. Thus, the projections 40b are immediately cammed over the lugs 45a (Fig. 8) so that the rear ends of the locking elements 40 are pushed outwardly with respect to the platform. This rocks the locking elements 40 on the shaft 41, causing the fingers 40a to extend through the apertures 44 (Fig. 8) and into locking engagement with the ribs 22 of any hopper 11 which happens to be supported on the platform. The lugs 45a and projections 40b therefore assure that the fingers 40a are adequately extended to lock a hopper in place even though the platform is only slightly tilted. No sliding of the hopper on the platform can occur.

As the platform continues to swing downwardly to its dumping position (Fig. 9), the stationary cams 45 become more nearly disposed at right angles to the platform. The rear ends of the locking elements thus bear against the cams and are held outwardly from the platform. The fingers 40a are, as a result, held in projected relation through the apertures 44 and in locking relation with the ribs 22 of a hopper on the platform. Because the projections 40b clear the rear ends of the cams 45, and the flat surfaces of the elements 40 bear against the cams, there is no tendency to push the fingers 40a farther than necessary through the apertures 44.

When the latching bolts 32 are retracted, therefore, the platform 28 and hopper 11 thereon automatically tilt forwardly since a major portion of their weight is disposed

forwardly of the rod 29. Such tilting is limited, however, by engagement of the fingers 40a with the edges of the apertures 44 (Figs. 2 and 9), whereby the hopper is not turned completely upside down. Nevertheless, it is tilted through more than 90 degrees to a substantially upside down position such that material is dumped through the upper opening of the hopper body 20. There is no necessity for a trap door or swinging gate, with attendant latching means, on the hopper body. It will be observed that the fingers 40a lock the hopper against sliding forwardly relative to the platform. But when the latter is rocked through more than 90 degrees from its horizontal position, the flanges 25, which define the channels 24 for receiving the platform 28, bear against the under side of the latter and prevent dropping of the hopper.

It is believed that the operation of the illustrative materials handling apparatus will be clear from the foregoing description. However, by way of recapitulation, it may be stated that with the platform 28 held in its horizontal position by the latch bolts 32, it may be horizontally inserted and retracted from the under side of the hoppers 11, preferably into and from the channels 24 formed by the flanges 25 and the bottom of the body 11. With the platform so inserted beneath the hopper 11, the latter may be raised on the fork truck 12 and transported in the usual conventional manner. Thus, in certain applications where a dumping operation is not required, the full utility of the fork truck and hoppers are retained. Additionally, however, when a loaded hopper 11 is to be dumped into an elevated receiving receptacle, such as the bin 14, it is only necessary for the operator to drive the truck 12 directly up to the bin 14, and pull on the chain 38 to thereby retract the latch bolts 32. The platform and hopper then swing forwardly about the rod 29 under the influence of their own weight. As an incident to such tilting of the platform, the stationary cams 45 push the rear ends of the locking elements 40 away from the under side of the platform, causing the fingers 40a to extend through the apertures 44 and into locking engagement with the ribs 22 of the hopper. The fingers 40a thus automatically lock the hopper against forward sliding movement as the platform 28 tilts. Complete dumping of materials in the hopper is assured since it is tilted through more than 90 degrees to a substantially upside down position (Fig. 2). In this position, the flanges 25 bear against the under side of the platform 28 and prevent dropping of the hopper.

In order to return the platform 28 and the emptied hopper 11 to their original positions, the operator simply causes lowering of the elevator carriage 12d so that the hopper strikes guard strips 48 (Figs. 1 and 2) placed on the receiving bin 14. Further lowering, and slight forward movement of the truck 12 if necessary, rocks the platform 28 rearwardly until its aft edge cams past the latch bolts 32 and the latter snap into holding engagement with the stop flange 28a.

The empty hopper may then be transported to any desired point, discharged from the platform 28 in the usual manner, and another hopper picked up.

Numerous advantages accrue from the use of the novel attachment and hopper of the present invention, especially as compared to prior dumping attachments of the type which require power means and which rotate a hopper about an axis running fore and aft of the fork truck. In the present case, no power drive to the dumper attachment is required, and it adds weight in the order of only 100 pounds to the elevating carriage, as contrasted with 300 to 400 pounds for the prior devices. Since the present attachment tilts forwardly of the fork truck, as opposed to sidewise in the prior devices, the truck may be driven forwardly right up to the receiving bin. In tight quarters, this is important. Moreover, it permits the hopper to extend completely over the receiving bin, so that if the hopper should, by some chance, fall, it drops into the bin rather than onto the floor where it might injure a workman.

I claim as my invention:

1. Materials handling apparatus for affording dumping of loads from an elevated position on a fork lift truck, said apparatus comprising the combination of a hopper having transverse ribs on its underside, legs for supporting the hopper in elevated position, and means spaced below the underside of the hopper to define spaced horizontal channels; with an attachment for the fork lift truck including at least one L-shaped member adapted for connection to the truck in lieu of its forks, said L-shaped member having a horizontal portion, a platform, means pivotally connecting the said platform to the horizontal portion of said L-shaped member to afford swinging movement of the platform between horizontal and forwardly tilted positions, said platform being insertable into said channels beneath said hopper, there being at least one aperture defined in said platform, and means automatically projected upwardly through said aperture into locking engagement with one of said ribs on said hopper as an incident to forward tilting of said platform relative to said L-shaped support member.

2. Materials handling apparatus for affording dumping of loads from an elevated position on a fork lift truck, said apparatus comprising, in combination, an attachment for the truck including a pair of L-shaped members adapted for connection to the truck in lieu of its forks and presenting forwardly extending horizontal arms, a plate-like platform, means pivotally connecting said platform to said arms for swinging movement between horizontal and forwardly tilted positions, releasable latch means for retaining said platform in its horizontal position, there being a plurality of apertures defined in said platform, a corresponding plurality of locking fingers pivotally mounted beneath said platform, cam means mounted in fixed relation to said horizontal arms and engaged by said fingers for automatically extending and retracting said fingers through said apertures when said platform is in its tilted and horizontal positions, respectively; and a hopper having transverse ribs on its underside, and means spaced beneath the underside of the hopper to define spaced horizontal channels running at right angles to said ribs; whereby said hopper may be lifted and transported by inserting said platform into said channels, and said fingers automatically engage said ribs to lock said hopper on said platform when said latch means are released to dump the hopper forwardly.

3. Materials handling apparatus for affording dumping of a hopper having ribs on its underside, said apparatus comprising, in combination, at least one support member adapted for connection to a raising and lowering mechanism and presenting a horizontally extending arm, a platform, means pivotally connecting said platform in overlying relation to said arm for swinging movement between horizontal and tilted positions, said platform when in its horizontal position being insertable beneath the hopper to elevate the same, there being at least one aperture defined in said platform, and means beneath said platform retracted from said aperture when the platform is horizontal and extended through said aperture into locking relation with the hopper ribs as an incident to tilting of the platform, whereby the hopper is locked to the platform when the latter is tilted to dump the former.

4. In materials handling apparatus, the combination of a hopper having spaced parallel ribs on its bottom and means spaced beneath its bottom defining therewith a channel running at right angles to said ribs; of means for supporting and dumping said hopper comprising a platform, a stationary cam, means pivotally supporting said platform for rocking movement relative to said cam and between substantially horizontal and tilted positions, said platform being adapted when horizontal for entry into said hopper channel, and a locking element mounted on said platform for bodily movement therewith and for relative movement thereto between projected and re-

tracted positions, said locking element being located to cooperatively engage said cam so that it is shifted by the latter from its retracted to its projected position as an incident to tilting movement of said platform relative to said cam.

5. Materials handling apparatus for affording dumping of a hopper having ribs on its underside from an elevated position on a fork lift truck, said apparatus comprising, in combination, a pair of support members adapted for connection to the truck in lieu of its forks and presenting horizontally extending arms, a platform, means pivotally connecting said platforms in overlying relation to said arms for swinging movement between horizontal and downwardly tilted positions, there being a plurality of apertures defined in said platform, a corresponding plurality of locking fingers beneath said platform and insertable through and retractable from said apertures, cam means mounted in fixed relation to said arms and operative on said fingers for holding the latter in retracted position when said platform is horizontal and for extending said fingers through said apertures as an incident to tilting of the platform, whereby said fingers engage the ribs of the hopper to retain the latter as the platform is tilted to effect dumping of the hopper contents.

6. Materials handling apparatus for affording dumping of a hopper having ribs on its underside from an elevated position on a fork lift truck, said apparatus comprising, in combination, a pair of L-shaped support members adapted for connection to the truck in lieu of its forks and presenting forwardly extending horizontal arms, a rod fixed between the forward ends of said arms, a platform pivotally mounted on said rod for rocking movement between a horizontal position and a forwardly, downwardly tilted position, there being a pair of apertures defined in said platform, a pair of locking elements pivotally mounted to the underside of said platform at a point forward of said rod and rearward of said apertures, said elements having upturned fingers at their forward ends located for projection through and retraction from said apertures as the elements rock relative to said plate, and a pair of cams fixed on said rod and engaged with the rearward ends of said locking elements to rock the latter relative to said platform as it pivots on said rod and to thereby cause projection of said fingers through said apertures as an incident to forward tilting of the platform.

7. Materials handling apparatus for affording dumping of a hopper having ribs on its underside from an elevated position on a fork lift truck, said apparatus comprising, in combination, a pair of L-shaped support members adapted for connection to the truck in lieu of its forks and presenting forwardly extending horizontal arms, a rod fixed between the forward ends of said arms, a platform pivotally mounted on said rod for rocking movement between a horizontal position and a forwardly, downwardly tilted position, there being a pair of apertures defined in said platform, a pair of locking elements pivotally mounted to the underside of said platform at a point forward of said rod and rearward of said apertures, said elements having upturned fingers at their forward ends located for projection through and retraction from said apertures as the elements rock relative to said plate, and a pair of cams fixed on said rod and engaged with the rearward ends of said locking elements, said cams extending horizontally from said rod and having depending lugs at their rear ends, said locking elements

having projections at their rear ends adapted to cam over said lugs, whereby said locking elements are rocked relative to said platform as it pivots on said rod to thereby cause projection of said fingers through said apertures as an incident to forward tilting of the platform.

8. In materials handling apparatus, the combination comprising a platform pivotally supported to rock between horizontal and tilted positions, locking fingers movably carried by and normally retracted beneath the upper surface of said platform and means for extending said fingers upwardly through said platform as incident to tilting of the latter, and a hopper which includes a body, a plurality of parallel ribs on the underside of said body, legs for supporting said body in elevated position above the ground or floor, a pair of plate-like members fixed in spaced relation to the underside of said body to define therewith spaced horizontal channels running transversely to said ribs and opening inwardly toward one another, said channels being adapted to receive the opposite side edges of said platform, whereby the locking fingers may engage said ribs to prevent sliding of the hopper relative to the plate, and said plate-like members support the hopper when the platform is turned substantially upside-down.

9. In materials handling apparatus, the combination of an apertured platform, means pivotally supporting said platform for rocking movement between substantially horizontal and tilted positions, a locking element pivotally mounted on the underside of said platform and adapted to have one end portion projected through said platform, a stationary cam disposed beneath said platform in position to be engaged by said locking element, said cam being notched to provide a depending lug, and a projection on the other end of said locking element nested in said cam when the platform is horizontal to afford retraction of said one end portion, said other end portion of said locking element riding over said cam to thereby rock the locking element relative to the platform and project the one end portion through the platform as incident to tilting of the latter.

10. In materials handling apparatus for supporting and dumping a hopper, the combination of a platform having an aperture therein, a stationary cam, means pivotally supporting said platform for rocking movement relative to said cam and between substantially horizontal and tilted positions, and a locking element mounted on said platform for bodily movement therewith and relative movement with respect thereto, said locking element having means cooperatively engaged with said cam and shifted thereby for moving the element between (a) a position projecting through said aperture into locking engagement with the underside of a hopper supported on said platform and (b) a position retracted from said aperture in response to said rocking movement of said platform between (a) tilted and (b) horizontal positions, respectively.
